UNITED STATES PATENT OFFICE.

THOMAS L. RIVERS, OF MOUNT VERNON, ILLINOIS, ASSIGNOR TO CHARLES B. LINDSEY, OF SAME PLACE.

HAME-TUG.

SPECIFICATION forming part of Letters Patent No. 297,634, dated April 29, 1884.

Application filed December 28, 1883. (No model.)

To all whom it may concern:

Be it known that I, THOMAS L. RIVERS, a citizen of the United States, residing at Mount Vernon, in the county of Jefferson and State of Illinois, have invented a new and useful Hame-Tug, of which the following is a specification, reference being had to the accompanying drawings.

My invention relates to hame-tugs; and it has for its object to provide a device of this character which shall be cheap and simple in its construction and thoroughly efficient in its use.

The invention consists in the improved construction and combinations of parts herein-after fully described, and pointed out in the claims.

In the drawings, Figure 1 is a front view of my improvements applied. Fig. 2 is a longitudinal section of the same. Fig. 3 is a rear view, in perspective, of the plate connecting the hame-tug with the trace; and Fig. 4 is a rear perspective view of one of the hame-tugs detached.

A represents two of my improved hame-tugs, connected by a link or loop, B. The said tugs each consist of the top portion, a, having formed therein a rectangular slot or opening, b, and a slightly smaller rectangular slot or opening, b', the same communicating with each other by means of a longitudinal slot, b², which forms an inwardly-projecting lug, b³, the same limiting the longitudinal play of the trace-catch when connected thereto, as will be more fully set forth. These hame-tugs A are formed with inwardly-projecting flanges c on each of their sides, and with hooks or catches d upon their inner sides and near their ends. Upon these hooks or catches d are attached the connecting-links B, for connecting the tugs when a series of the same are used, the end hook or catch, d', being attached to the loop or ring in the hame. The hame-tugs are formed upon their front sides with re-enforcing-strips e of the same form as the slots b b', and having the openings to correspond thereto.

C represents the trace-plate, which is secured to the trace by rivets or other suitable fastenings passing through the perforations in said plate. The trace-plate is formed upon its under side, and near the opposite end from

the perforations c', with an inwardly-projecting lug, D, which may be said to approximate a T shape in cross-section. This lug D is adapted to be inserted through the opening or slot b, and is then slid or passed through the slot b' into the slot or opening b', where it is securely held against disengagement or displacement, thus securing a firm and secure fastening between the hame-tugs and the trace 60 of the harness.

My improvements are applied in the following manner: As many of the tugs are used as is necessary, and the same connected by the loops or links B, the end hook of one of the 65 tugs engaging with the ring or loop upon the hame. The trace may then be attached to the tugs by inserting the lug which is formed upon the inner side of the trace-plate into the slot b, and then sliding it into the smaller opening 70 b', the T-shaped head of said lug engaging with the adjacent sides of the opening b', thus preventing any vertical movement of the same, and when draft is applied all tendency to longitudinal movement of the trace will be overcome.

Having fully described my invention, what I claim as new, and desire to secure by Letters Patent, is—

1. The combination of a series of hame-tugs, 80 having rectangular slots, hooks, or catches formed upon their inner sides, and with re-enforcing strips, said tugs being connected by links engaging with the hooks upon the under sides of said tugs, with a trace-plate having 85 an inwardly-projecting lug formed upon its inner side, substantially as set forth.

2. As an improved article of manufacture, a hame-tug having the slots or openings b b', communicating with each other by means of 90 the slot b², said tugs being formed upon their inner sides with hooks, and provided upon their outer sides with re-enforcing strips, in combination with a plate, C, formed with the lug D, substantially as described.

In testimony that I claim the foregoing as my own I have hereto affixed my signature in presence of two witnesses.

THOMAS L. RIVERS.
